UNITED STATES PATENT OFFICE

JOHN D. SEABERT, OF DAYTON, OHIO, ASSIGNOR TO GENERAL MOTORS RADIO CORPORATION, A CORPORATION OF OHIO

ACOUSTIC DEVICE

Application filed December 22, 1930. Serial No. 508,999.

This invention relates to an acoustic device and more particularly to acoustic devices such as loud speakers for mounting in the dome of automobiles.

5 In the conventional speakers or reproducers that are used for reproducing signals from radio receivers, phonographs and the like it is customary to provide a baffle, a sound chamber or the like which greatly improves the acoustic properties of the reproducer.

When reproducers are mounted in the dome of automobiles the space available for a baffle or for a sound chamber is so limited that a baffle extending radially from the periphery of the diaphragm cannot very well be used and due to the shallowness of the top of a car a suitable sound chamber cannot be provided. If either a baffle or a sound chamber were to be used the reproducer due to the 20 shallowness of the top would extend down so as to interfere with the comfort of the passengers.

An object of this invention is to eliminate the conventional sound chamber and the conventional baffle that extends radially from the periphery of the diaphragm. This has been accomplished by providing an internal baffle so constructed and arranged as to increase the length of the path of the sound waves especially the low frequency notes and so as to dampen the flow of air from one side of the diaphragm to the other thereby accomplishing the same results or substantially the same results as though a sound chamber were used 35 or a baffle extending radially from the diaphragm were used.

Another object of this invention is to provide a reproducer that is very shallow in comparison with its width. This has been accomplished by providing a reentrant diaphragm so as to reduce the altitude of the diaphragm.

45 Further objects and advantages of the present invention will be apparent from the following description, reference being had to the accompanying drawings wherein a preferred embodiment of one form of the present invention is clearly shown.

In the drawings:

50 Fig. 1 represents a front view of an acoustic

device part of which is shown in section, taken on the line 1—1 of Fig. 2.

Fig. 2 represents a section, taken on the line 2—2 of Fig. 1.

Referring to the drawings and particularly to Fig. 2, a main supporting disc or plate 20 has attached thereto a cup-shaped field housing 22, a center pole piece 24, and a reenforcing plate 26, adapted to increase the permeability of the base 28 of the field housing 22. A reduced portion 30 of the center pole piece 24 projects through an aperture of the field housing 22, the supporting plate 20 and the reenforcing plate 26 and is riveted thereto, thus securing the housing 22, center 65 pole piece 24 and plate 26 to the supporting plate 20. This could be accomplished in any other suitable and well known manner.

An annular pole piece 32, attached to the field housing 22 by spot welding or in any other suitable manner, carries a reenforcing ferro-magnetic ring 34, which is welded to or otherwise secured to the annular pole piece 32. The reenforcing ring 34 decreases the flux density through the air gap 33.

75 A magnetic coil 36, having two terminals 38 and 40, connected to either a source of direct current or to a source of rectified current so as to excite the magnetic field, links the center pole piece 24. Interposed between the uppermost layers of the field coil 36 and the annular pole piece 32 is a spacer of any soft packing material, that prevents axial movement of the field coil 36.

80 A reentrant diaphragm 42 that includes a pair of frusto-conical surfaces is held in position by a cloth ring 44. The edge of the reentrant diaphragm 42 is attached to the ring 44 by cement or any other suitable binding material. The cloth ring 44 has its outer 90 periphery clamped between a ringlike clamping member 48 of suitable shape and the border 50, provided by the annular ring plate or baffle 52 by screws 54. The baffle 52 is supported upon the hollow spacing members 95 56 through which extend the screws 58, threadedly engaging the baffle 52 as at 60. The baffle 52 of course can be supported and properly positioned by any other suitable means. As the annular pole piece 82 is very 100

closely located to the baffle 52 as its inside diameter is only slightly larger than the outside diameter of the annular pole piece 32, it is obvious that a relatively small amount of air can flow through the very limited space, in fact only a sufficient amount to compensate for the difference in air pressure in front and in the rear of the vibrating diaphragm 42 at any instant but never to allow free flow of air. The baffle 52 also increases the length of the path of the air from the inside of the diaphragm to the outside. This increase in the air path improves the acoustic properties of the reproducer. The restricted opening found between the baffle 52 and the annular pole piece 32 probably tends to reduce undesired reverberations, caused by the rather shallow type of reproducer.

The diaphragm 42 also carries a speech coil 62, wound upon a cylindrical support 64, which is cemented to or otherwise secured to the inner inclination of the diaphragm 42 as at 66.

In order to properly center the cylindrical support 64 with respect to the center pole piece 24 and the air gap 33 between the center pole piece 24 and the annular pole piece 32 and the reenforcing plate 34, a spider 68 is cemented to or otherwise secured to the inner inclination of the diaphragm 42 as at 70 and fastened to a reduced portion 72 of the center pole piece 24 by a screw 74. The spider 68 allows axial play of the cylindrical support 64 with the speech coil 62, but prevents any radial deflection thereof. The spider 68 and the flexible ring 44 exert a restoring force upon the diaphragm whenever the diaphragm is displaced.

A cover plate or grille 76 of suitable design, provided with several openings 78 to allow sufficient air to flow through is supported by the studs 80, riveted at 82 to the supporting plate 20 and located by the screws 84, threaded into the studs 80.

Operation

Whenever the diaphragm of a reproducer is displaced due to the flow of signal current through the speech coil unequal air pressure will result on opposite sides of the diaphragm. If no baffle or the like is used the air tends to flow around the edge of the diaphragm from the high pressure to the low pressure side, thereby equalizing the pressure without any substantial displacement of the air away from the diaphragm, thereby greatly reducing the efficiency of the reproducer. Unless the displacement is extremely large the internal baffle plate 52 prevents a free flow of air from the high pressure side to the low pressure side of the diaphragm, thereby preventing a too sudden equalization of the unequal air pressure on the opposite sides of the diaphragm, but at the same time permitting a sufficient flow of air either into or out

of the cavity 90 found intermediate the baffle 52 and the diaphragm 42. It has been found that the baffle 52 accomplishes the same result as though either a sound chamber or an external baffle extending outwardly from the diaphragm were used.

The leakage effect of the baffle 52 may be further controlled by suitable perforations, not shown, if this is found desirable.

While the form of embodiment of the present invention as herein disclosed, constitutes a preferred form, it is to be understood that other forms might be adopted, all coming within the scope of the claims which follow.

What is claimed is as follows:

1. A reproducer for automobile use, comprising a supporting disc, a reentrant diaphragm, supports for supporting the reentrant diaphragm in spaced relation with respect to said disc, a movement mounted intermediate said disc and said diaphragm, and an internal baffle extending from the outer periphery of the diaphragm inwardly towards said movement whereby the free flow of air from one side of the diaphragm to the other is limited.

2. A reproducer for reproducing sound in response to electrical impulses, a diaphragm, a movement for actuating said diaphragm, a disc-like frame for supporting said diaphragm and said movement in spaced relation, and an internal baffle extending inwardly from the outer periphery of the diaphragm, so as to increase the length of the path of the air from one side of the diaphragm to the other.

3. An acoustic device, comprising, a diaphragm, a baffle extending radially from the outer periphery of said diaphragm, said baffle having an annular flange, and an annular clamping member cooperating with the flange to clamp the edge of the diaphragm.

4. An acoustic device, comprising in combination, a diaphragm, a baffle extending inwardly from the edge of the diaphragm, said baffle having an annular flange at the outer periphery, an annular clamping member having a flange, the outer edge of the diaphragm being clamped between the flange of said baffle and the flange of said clamping member.

5. An acoustic device, comprising in combination, a housing including a disc shaped member, a diaphragm, supporting members attached to said housing for supporting said diaphragm, and a grille mounted opposite said housing for protecting the diaphragm, supports for said grille, said supports for the grille being independent of the supports carrying the diaphragm.

6. An acoustic device, comprising in combination, a disc-shaped housing, a plurality of rows of concentric rows of supports carried by said housing, a diaphragm, and an inwardly extending baffle support on one row

of supports and a grille protecting said diaphragm supported on another row of supports.

7. An acoustic device, comprising in combination, a disc-shaped frame, a movement mounted in the center of said frame, a plurality of concentric rows of supports carried by said frame, an annular baffle carried by one of said rows, a diaphragm mounted on an edge of said baffle, said diaphragm being actuated by said movement, and a grille for protecting said diaphragm mounted on another row of said concentric supports.

8. In an acoustic device, a frame, a driving movement mounted on said frame, a diaphragm, a grille, and a plurality of rows of supports, one of said rows of supports supporting the diaphragm and another row the grille whereby the grille and the diaphragm are mounted on independent supports.

In testimony whereof I hereto affix my signature.

JOHN D. SEABERT.
